(57) **CLAIM**

We claim, the ornamental design for a data transmission cable, as shown and described.

DESCRIPTION

FIG. 1 is a perspective view of a data transmission cable, showing our new design;

FIG. 2 is another perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

Portions shown in broken lines form no part of the claimed design. The wavy break lines shown in FIGS. 1, 2 and 5-8 symbolize breaks in the length of the article in which the claimed design is embodied. The appearance of the wavy break lines and any portion of the article between the break lines forms no part of the claimed design.
